(57) **CLAIM**

The ornamental design for a camouflage tree bark relief hunting shirt, as shown and described.

DESCRIPTION

The present invention relates generally to camouflage hunting clothing, and more specifically, to camouflage hunting shirt having a relief pattern indicative of tree bark.

FIG. 1 is a front view of a camouflage pine tree bark relief hunting shirt;

FIG. 2 is a rear view thereof;

FIG. 3 is a right side view thereof;

FIG. 4 is a left side view thereof;

FIG. 5 is a bottom view thereof; and,

FIG. 6 is a top view thereof.
